VENTILATED CRATE

Richard H. Fletcher, Hamburg, N. Y.

Application June 16, 1938, Serial No. 214,094

4 Claims. (Cl. 217—42)

My invention relates in general to crates, and particularly to crates which are so designed that when stacked for shipment, suitable ventilation will be provided around and through the adjacent crates.

One of the objects of my invention has been to provide a crate having a complete frame at the top and bottom thereof, whereby adequate nailing surface is provided for the slats at the sides, ends, and bottom of the crate, thus resulting in a rigid construction.

Another object has been to provide end strips on the upper frame which are thicker than the end strips on the bottom frame, whereby ventilating spaces will be provided.

Moreover, it is an object to permit the side strips of the bottom frame to extend beyond the end strip of the frame to act as stops or spacers for the bottom frame.

Another object has been to provide a construction in which short slats at the bottom and sides may be used, thus reducing the cost of the crate.

The above objects and advantages have been accomplished by the device shown in the accompanying drawing, of which:

Fig. 1 is a perspective view of my invention, with the cover removed.

Fig. 2 shows a fragmentary, sectional, side elevation of two crates in shipping position, taken through both crates on a line represented by line 2—2 of Fig. 1.

Fig. 3 is a fragmentary, top, plan view of one corner of the crate.

Fig. 4 is a fragmentary, sectional, plan view of the same corner of the crate showing the bottom of the crate, and taken on line 4—4 of Fig. 1.

My crate comprises a top frame 10 and a bottom frame 11. The top frame comprises two side strips 12 which are joined together by two end strips 13, the end strips being preferably fitted between the side strips. The end strips of the top frame are thicker than the end strips of the bottom frame for purposes of ventilation, to be hereinafter described.

The dimensions of the end strips are, of course, not material, but for illustrative purposes I may use $\frac{3}{4}$ inch stock for the end strips 13 of the top frame 10 and $\frac{7}{16}$ inch stock for the end strips 15 of the bottom frame 11. The side strips 12 and 14 of the top and

bottom frames 10 and 11, respectively, may be $\frac{7}{16}$ inch stock. The width of the stock in the present instance for both end and side strips is about $1\frac{1}{2}$ inches.

By this construction, it will be obvious from Fig. 2 that when two crates are placed end-to-

end, the adjacent end strips 13 of the upper frames 10 of the two crates will contact, but that there will be a space 17 between the adjacent end strips 15 of the lower frames 11, whereby adequate ventilation will be provided for in between the crates. In order to be assured that adjacent crates will be kept suitably spaced apart, I may allow the ends of the side strips 14 of the lower frame to extend beyond the outer faces of the end strips 15, thus forming projections 16. The length of the side strips 14 of the lower frame 11 are substantially the same as the length of the side strips 12 of the upper frame 10, whereby the outer faces of the projections 16 are in line with the ends of the side strips 12 of the top frame 10. These coating, abutting projections 16 serve to enclose the outer ends of the space 17, thus defining the space and tending to induce a draft of air upwardly therethrough.

It will, therefore, be impossible to bring the end strips 15 of the lower frame of the adjacent crates in contact with each other, thus always providing for ventilation. Obviously, when the adjacent ends 13 are in contact, the faces of the projections 16 of the two adjacent crates are in abutting relation with each other.

By having complete upper and lower frames 10 and 11, respectively, it is possible to manufacture my crate with great economy for the reason that ample nailing surfaces are provided at both the top and the bottom of the crate and, therefore, relatively short slats may be used for the bottom as well as the sides and ends of the crate. The slats 20 at the bottom may be extended across from one side strip 14 to the other side strip because of the frame construction. The same thing applies to the side slats 21 and the end slats 22, which slats are secured at their lower ends to the inner faces of the side strips 14 and end strips 15 of the lower frame 11, respectively, and whose upper ends are secured to the inner faces of the side strips 12 and ends 13 of the upper frame 10, respectively.

To give added strength and to reinforce the bottom slats 20, a number of skid slats 23 are placed longitudinally along the bottom of the crate, which are secured to the side and end strips of the bottom frame and preferably to each bottom slat 20.

In Fig. 2, I have shown each crate provided with its cover or lid 24, having a cross strip 25 at each end.

From the foregoing it will be clear, as hereinbefore indicated, that when two crates are placed end-to-end, as when being stored or shipped,

the end strips 13 of the upper frame 10 may be brought tightly together with the assurance that sufficient ventilation will be provided at the bottoms and sides of the crate and between the 5 adjacent end strips 15 of the bottom frames 11, and that the end strips 15 will be positively spaced apart, due to the projections 16 whose end faces also abut one another when such projections are provided.

10 While I have shown and described the projections 16, it is obvious that the side strips 14 may extend only to the outer faces of the end strips 15 since, when each adjacent crate is sitting on its bottom and the relatively thick end strips 13 of the upper frames are in contact, the end strips 15 of the lower frame will be kept in spaced relation, thus providing the desired ventilating space.

Obviously, some modifications of the details herein shown and described may be made without departing from the spirit of my invention or the scope of the appended claims, and I do not, therefore, wish to be limited to the exact embodiment herein shown and described, the form shown being merely a preferred embodiment thereof.

25 Having thus described my invention, what I claim is:

1. A crate comprising a top frame formed of end strips and side strips, the side strips overlapping the end surfaces of the end strips, a 30 lower frame having end strips and side strips, the end strips of the lower frame being thinner than the end strips of the upper frame, the side strips of the lower frame extending beyond the end strips thereof and being coextensive with the 35 side strips of the upper frame, whereby spacing projections are formed at the ends of the side strips of the lower frame for enclosing the vertical air channel formed between the end strips thereof, and side, end, and bottom walls secured 40 to the end and side strips of the crate frames, said end walls being formed with ventilating openings, whereby air currents will be permitted to freely pass upwardly over the ends of the crate and through the openings between the slats 45 thereof.

2. A crate comprising an upper frame and a lower frame, each frame comprising end strips and side strips extending continuously and horizontally around the crate, side walls and end 50 walls fastened to and connecting the upper and lower frames, said end walls being formed of interspaced slats to provide suitable ventilating openings, and a bottom extending across the lower frame, the end strips of the upper frame 55 being thicker than the end strips of the lower frame, the end strips at each end of the crate

being so positioned as to have their inner faces lying in substantially the same vertical plane, the side strips of the lower frame having their end surfaces lying in substantially the same vertical plane as the outer surfaces of the end strips 5 of the upper frame, whereby spacing projections are formed at the ends of lower frames and air currents will be permitted to freely pass upwardly over the ends of the crate and through the openings between the slats thereof.

3. A crate comprising an upper frame and a lower frame, each frame comprising end strips and side strips extending continuously and horizontally around the crate, side walls and end walls fastened to and connecting the upper and 15 lower frames, said end walls being formed of interspaced slats to provide suitable ventilating openings, and a bottom extending across the lower frame, the end strips of the upper frame being thicker than the end strips of the lower 20 frame, the end strips at each end of the crate being so positioned as to have their inner faces lying in substantially the same vertical plane, the side strips of the lower frame having their ends extending beyond the outer faces of the end strips of the lower frame, whereby spacing 25 projections are formed at the ends of lower frames and air currents will be permitted to freely pass upwardly over the ends of the crate and through the openings between the slats thereof.

4. A crate comprising an upper frame and a lower frame of substantially the same inner dimensions, each frame comprising end strips and side strips joined together at the ends and extending continuously and horizontally around the crate, side walls and end walls secured to the inner sides of said upper and lower strips forming the frames and connecting them in spaced relation, said end walls and side walls being formed of vertical, transversely spaced slats to 40 provide suitable ventilating openings extending from the bottom frame to the top frame, and a bottom extending across the lower frame, the end strips of the upper frame being thicker than the end strips of the lower frame, and the corresponding side strips of the upper and lower frames being of substantially the same thickness whereby the end strips of the upper frames of adjacent crates abut one another to space the end strips of the lower frames to provide a ventilating space 50 between said adjacent end pieces of the lower frames, whereby air currents will be permitted to freely pass upwardly over the ends of the crates through the openings between the slats 55 thereof.

RICHARD H. FLETCHER.
